UNITED STATES PATENT OFFICE.

WILLIAM H. BOZARTH, OF VINELAND, NEW JERSEY.

OIL BURNER FOR FURNACES.

Application filed September 4, 1920. Serial No. 408,159.

To all whom it may concern:

Be it known that I, WILLIAM H. BOZARTH, a citizen of the United States, residing at Vineland, county of Cumberland, and State of New Jersey, have invented new and useful Improvements in Oil Burners for Furnaces, of which the following is a specification.

This invention relates to oil burners for furnaces, and particularly to a burner to be fitted to a furnace to use the lighter oils and to operate under forced feed.

An object is to provide a burner adaptable to be constructed for and readily fitted with in a furnace having a fire pot of circular, rectangular, or other form, and which will direct the flame to secure a maximum heating efficiency for the fuel consumed.

A further object resides in constructing the burner in such a manner that it can be readily fitted to and removed from a furnace already installed, and can be made of a size to fill the fire pot.

Yet another object lies in providing a generating system including subgenerator and generators to supply a pilot and the burner.

A still further object is to so construct and arrange the subgenerator and generators that a proper flow of gas to the burner will be maintained during use, and a sufficient volume will be generated by the pilot system when the burner is extinguished to insure instant combustion when the burner is lighted.

With these and other objects in view, which will be apparent from the drawings, specification and claims, this invention includes certain novel features of construction and combinations of parts which will now be set forth.

In the drawings:

Figure 1 is a top plan view of a circular burner constructed in accordance with my invention.

Fig. 2 is a vertical sectional view through the structure.

Fig. 3 is a view in elevation from the feed end with the burner in section to more clearly illustrate the construction.

Fig. 4 is a view in elevation from the opposite end.

Fig. 5 is a perspective view of the generator burners.

Fig. 6 is a transverse sectional view through one of the generator tubes.

Fig. 7 is a fragmentary sectional view showing in detail the manner of connecting the burner sections together.

The burner here illustrated is adapted to be supported upon the grate of a furnace already in use to thus be within the fire pot, and to direct its flames in a manner to accomplish greatest efficiency. With this in mind the legs or supports 1 and 2 are provided, these supports having feet 3 which rest upon the furnace grate.

The burner 4 is mounted directly on these legs or supports, and is thus elevated above the grate to direct its flames at a point within the fire pot to secure maximum heating efficiency. The burner is here shown as made of circular form to fit within a circular fire pot, although it might be of other configuration to conform to other shapes of grates and fire pots.

By experimentation it has been found that a burner structure made up in a single piece is fitted only with greatest difficulty and that it must be of relatively smaller size than the fire pot in which it is to be used. To overcome this difficulty I construct my burner in two sections which are readily assembled when fitted to the furnace, and which can be made to entirely fill the fire pot. The burner is made up in two semi-circular sections 5 and 6, and these sections are connected together in the manner best shown in Fig. 7. The bevel-edged strips 7 and 8 are secured vertically on the ends of the section 6 by means of bolts 9, or other fastenings, and provide a dovetailed socket. A dovetail locking strip 10 is secured on each end of the section 5 by means of bolts 11, and is shaped to fit the socket between strips 7 and 8. With this construction of the burner, the sections 5 and 6 can be separately inserted through the door of the furnace and then when the locking strips 10 are fitted between strips 7 and 8 the semi-circular sections will be joined to present a continuous circle, the supporting legs 1 and 2 bearing the weight of the burner and retaining the sections in horizontal alignment.

Each of the semicircular sections has an independent gas chamber, which gas chambers supply three banks of burner openings, an inner bank 12, an outer bank 13, and a central bank 14. The middle bank or burner openings is elevated above the inner and outer banks, and the inner and outer burner openings are inclined toward and away from

the center of the circle of the burner. These burner openings are formed through lava or other suitable strips 15, 16, and 17, which are mounted substantially as shown in Fig. 5, the purpose of the angular disposition being to direct the flame from the outer burner openings 13 against the sides of the furnace fire pot, while the flame from the inner circle of burner openings is directed angularly inwardly. It has been found that the burner openings are best formed through the lava strips in substantially the manner shown in Fig. 1, as in this way a number of small independent flames are combined to form a single cone and the heat is concentrated more effectually. It is desirable that screens be provided beneath the lava burner strips, as shown at 17, in Fig. 3.

With the construction of the burner in two or several parts it is necessary that a gas supply be established to the chamber of each part, and this is accomplished in the present instance through supply pipes 18 and 19, these supply pipes leading from three-way connections 20 and 21. To maintain an even flow of gas through all of the burner openings it is preferable that the burner plate 17 be left blank above the discharge ends of these pipes 18 and 19, which pipes open through the bottom of the burner members 5 and 6, so that the gas will pass to the chambers thereof and will flow at uniform pressure through the burner openings.

To supply gas to and provide for substantially instantaneous generation and ignition at the burner, I provide generators and a subgenerator. An air box 22 is positioned beneath the burner ring adjacent the inner side of the open center thereof, and is divided into three various compartments 23, 24 and 25. Generator tubes 26 and 27 lead from the outer side of the burner and have their inner ends received through openings into the outer compartments 23 and 25, a subgenerator tube being positioned intermediate between generator tubes 26 and 27 and having its inner end extending into compartment 24. The sub and generator tubes are substantially identical in construction, and as shown in Fig. 2, have heads 29 at their inner ends which are provided with small gas escape openings 30, union nipples 31 being connected on the outer ends of these three tubes. A bar 32 adapted to receive the squared portions of nipples 31 and to support the outer ends of the tubes are carried by rods 33 which are connected on supporting standard 1. A bar 34 is provided with grooves to receive and support tubes, not here illustrated, having connection with the nipples 31, and by which kerosene or other fuel oil is supplied to the tubes. Wick structures made up of a case 35 of steel wire fabric or like material having shredded asbestos packed in the center thereof as at 36

is placed within each of the tubes 26, 27, and 28, and each tube has a strainer screen provided at 37 adjacent gas discharge opening 30.

The operation of the generator and subgenerator tubes requires the application of heat to raise temperature sufficiently to gasify the volatile oil as it is carried along by the wick structures, and this heating of the tubes is accomplished through the burner structure best shown in Fig. 5. This structure includes elongated gas burners 37 and 38 located beneath generator tubes 26 and 27, and a combination gas and liquid fuel burner 39 extending beneath subgenerator tube 28. Gas is supplied to burners 37 and 38 from three-way connections 20 and 21, and burner 39 receives its gas supply through pipe 40. Gas pipes 41 and 42 open into chambers 23 and 25 in line with the gas discharge openings from generator tubes 26 and 27, and these gas pipes are looped down and back to join with connections 20 and 21. The gas pipe 40 is looped upwardly, as shown in Fig. 2, and opens into compartment 24 in line with discharge opening 30 of subgenerator tube 28.

A hollow head 43 is provided in conjunction with burner 39 and has burners 44 and 45 which are disposed beneath the inner ends of generator tubes 26 and 27 and substantially in line with burners 37 and 38. Pilot tubes 46 and 47 lead from the gas chamber in head 43 and have their burner tips adjacent the inner and middle rings of burner openings in the main burner. Combination burner 39 has wicks 48 extending along each side thereof to receive liquid fuel and to direct the flame therefrom against subgenerator tube 28.

In the use of my improved oil burner, the parts are assembled in a furnace in the manner set forth, and independent supply pipes, having controlling valves therein, are connected with each of the tubes 26, 27 and 28. These oil supply tubes lead from a tank, or other source of supply, from which oil is fed under substantially 20 pounds pressure. Alcohol or other highly volatile oil is poured upon wicks 48 of burner 39, and these wicks are lighted. The flame from the wicks causes subgenerator tube 28 to be heated, and when the tube has been raised to a generating temperature the valve of the oil supply thereto is opened. As oil is supplied to the outer end of the tube it is taken up and advanced by the wick formation therein, and upon being brought to the proper temperature is gasified. The gas, under the pressure of the oil supply and its own expansive force, is discharged in a jet through openings 30 and into the open end of pipe 40 air being taken in from compartment 24 of the air box and mixed with the gas.

The gas travels down through pipe 40 and

is supplied to burner 39 and head 43. The gas flowing at burners 39, 44 and 45, and at the pilot tips on tubes 46 and 47, is lighted and these flames are kept burning at all times. The flame at burner 39 heats subgenerator tube 28 sufficiently to generate gas to supply this burner, burners 44 and 45, and the pilot burners. Burners 44 and 45 heat generator tubes 26 and 27 at their inner 5 ends and keep the same sufficiently hot that when oil is supplied thereto the oil will be substantially instantaneously volatilized and an immediate supply of gas will be furnished through gas pipes 41 and 42 when oil 10 is supplied to the generator tubes. A portion of the gas passing through these pipes is consumed by burners 37 and 38 to heat the generator tubes to proper generating temperature, and the remainder of the gas is 15 carried through pipes 18 and 19 to the gas chambers of the main burner. As the gas escapes from the burner openings it is ignited by the pilots, and the burner shows flame over its entire area. If desired, the 20 top of the air box might be made removable to give access to clean the gas discharge openings of the sub and generator tubes, however it has been found that the formation 25 of carbon and the collection of other residuary matter within the tubes is almost negligible.

While, in the foregoing, I have described specific embodiments, and have mentioned only certain possible modifications, it will be 30 appreciated that in practice I do not limit myself to such specific details as herein set forth, but may resort to any practical modifications falling within the scope of the invention as defined in the appended claims.

40 I claim:

1. An oil burner to be fitted for use in furnaces comprising a pair of substantially semi-circular burner members to be fitted within the furnace, and dove-tail connections by which the burner parts are readily

assembled by being moved vertically one with respect to the other and are held in assembled relation, said burner having burner openings to spread the flame and direct the same against the sides of the furnace structure. 50

2. An oil burner to be fitted for use in furnaces including with a gas consuming burner made in parts to be more readily fitted within the furnace, dove-tail connections by which the burner parts are held in assembled position, and generator structure beneath the burner to volatilize oil to supply gas to the burner, said generator structure being vertically beneath and entirely within 55 the confines of the burner to thus avoid obstructing and interfering with fitting and assembling the burner. 60

3. An oil burner for furnaces including with a gas consuming burner to be fitted in the fire pot of the furnace, supporting legs by which said burner is maintained at an elevation above the furnace grate, an air box supported beneath the burner at one side, horizontally disposed generator tubes 65 to be connected with an oil supply having their inner ends extended into the air box and provided with gas discharge openings, gas supply pipes receiving gas from the discharge openings of the generator tubes 70 and extended to conduct the gas to the burner, a subgenerator tube, a subgenerator burner located beneath the subgenerator tube provided with an extension head adjacent the air box, pilot burners on said extension head beneath the generator tubes, 75 pipes from said extension head provided with pilot tips adjacent the burner openings of the main burner, and a gas conveying pipe conducting gas formed in said subgenerator tube to the subgenerator burner and the extension head thereof. 80

85 In testimony whereof, I affix my signature.

WILLIAM H. BOZARTH.
